[57] **CLAIM**

The ornamental design for a ski and ski pole carrier, as shown and described.

DESCRIPTION

FIG. 1 is a top front perspective view of a ski and ski pole carrier showing my new design in its assembled, closed position;

FIG. 2 is a plan view showing the bottom of the ski and ski pole carrier in its assembled, closed position.

FIG. 3 is an exploded top rear perspective view thereof; and

FIG. 4 is a plan view showing the bottom of the ski carrier in its closed position without the ski pole carrier attached.

FIG 1

FIG 2

FIG 3

FIG 4
